(57) **CLAIM**

The ornamental design for a pressurized camp shower, as shown and described.

DESCRIPTION

FIG. 1 is a front perspective view of a pressurized camp shower, showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in FIGS. 1-6 represent stitching, and form part of the claimed invention. The boundary lines shown in FIG. 8 are for the purpose of illustrating portions of the pressurized camp shower that form no part of the claimed design. The mesh pattern is fragmentarily shown for convenience of illustration. It is understood that the pattern is uniformly continuous over the strap.
